SYNCHRONIZED CONVEYER MECHANISM
AND PRINTING PRESS

Frederick W. Hill, Rutherford, N. J., assignor to
General Printing Ink Corporation, New York,
N. Y., a corporation of Delaware

Application October 30, 1940, Serial No. 363,539

19 Claims. (Cl. 101—232)

My invention relates to a printing press having synchronized therewith a conveyer mechanism serving to move articles toward and from the printing zone.

My invention, in a broad aspect thereof, relates to an arrangement of the character stated wherein means is provided for transporting articles in succession along paths angularly related to each other, one of said paths extending through the printing zone.

My invention has more detailed reference to a printing press comprising means for moving strip-like articles endwise along a path extending through a printing zone, said articles being moved sidewise into and from said path by conveyers synchronized with the printing press.

Various other objects, advantages and features of my invention will become apparent from the following detailed description.

My invention resides in the synchronized conveyer mechanism and printing press, features and combinations of the character hereinafter described and claimed.

For an understanding of my invention and for an illustration of one of the forms thereof, reference is to be had to the accompanying drawings, in which:

Figure 1 is a front elevational view, with parts omitted, showing the apparatus of my invention.

Fig. 2 is an enlarged plan view, partly broken away, showing the mechanism for delivering strip-like articles to the printing press;

Fig. 3 is a perspective view showing part of a sprocket chain serving to remove strip-like articles from the path taken thereby while travelling through the printing press;

Fig. 4 is a plan view showing the mechanism for removing strip-like articles from the path taken thereby while travelling through the printing press;

Fig. 5 is an elevational view of the mechanism shown in Fig. 4;

Fig. 6 is a detailed elevational view showing the actuating mechanism for the arrangement which feeds strip-like articles directly to the printing press;

Fig. 7 is an enlarged elevational view, with parts omitted, showing the mechanism for delivering strip-like articles into the path taken thereby while travelling through the printing press;

Fig. 8 is an enlarged vertical sectional view, partly in elevation, taken on the line 8—8 of Fig. 7 looking in the direction of the arrows;

Fig. 8a is a vertical sectional view, partly in elevation, showing a feature of the invention;

Fig. 9 is an elevational view, partly in section, showing a pawl and ratchet mechanism;

Fig. 10 is a perspective view showing part of a sprocket chain serving to deliver strip-like articles into the path taken thereby while travelling through the printing press;

Fig. 11 is an enlarged elevational view, partly in section, showing the actuating means for the mechanism which removes the strip-like articles from the path taken thereby while travelling through the printing press;

Fig. 12 is an elevational view of the mechanism shown in Fig. 13; and

Fig. 13 is an enlarged, vertical sectional view, partly in elevation, taken on the line 13—13 of Fig. 1 looking in the direction of the arrows.

In general, my invention relates to an arrangement for printing on strip-like articles any desired representations, characters, marks or the like. With the form of the invention herein illustrated, although not necessarily, the strip-like articles are steel blanks which are passed endwise through the printing zone in order to print thereon numerals, transverse lines of different length, etc. whereby the blanks, after completion of the printing operation, are rulers of the character known to the art as "steel rulers."

Referring to Fig. 1, B represents a suitable base on which is supported a vertical main frame F having an upper extension f and a side extension f1. The base B also supports an electric motor 1 receiving energy from any suitable source, not shown. The armature of the motor 1 carries a gear wheel 2 which meshes with and drives a gear wheel 3 of a suitable gear box 4, power from which is delivered by an endless belt 5 to a pulley 6 mounted on a shaft 7 horizontally mounted in suitable manner in the frame extension f1. The shaft 7 has secured thereto for rotatable movement therewith a gear wheel 9 which meshes with and drives a train of gear wheels 10, 11, 12 and 13, Figs. 1 and 6, all of said gear wheels being mounted, respectively, on suitably journaled shafts.

Further, the gear wheel 9 meshes with and drives a gear wheel 14 secured to and rotatable with a shaft 15 horizontally mounted in the main frame F, the shaft 15 serving as the support for the impression or supporting cylinder 16. The gear wheel 14 meshes with and drives a gear wheel 17 secured to and rotatable with a shaft 18 mounted in the upper frame extension

f. the shaft 18 serving as the support for the blanket cylinder 19. The gear wheel 17 meshes with and drives a gear wheel 20 secured to and rotatable with a shaft 21 horizontally journaled in said upper frame extension *f*, the shaft 21 serving as the support for the plate cylinder 22.

Any suitable arrangement may be provided for applying ink to the plate cylinder 22. As herein shown, there is thus utilized a plurality of inking rollers 23, each of which receives ink in suitable manner from an inking drum 24 to which ink is supplied periodically by an oscillatory ductor roll 25 in turn receiving ink intermittently from a fountain roller 26.

As shown in Fig. 1, the hereinbefore described base B has secured thereto a lower horizontal supporting member 30 which, by the vertical struts 31, is adapted to support an angle member 32. As shown in Fig. 2, the member 32 has suitably secured thereto, as by the angles 33, a plurality of horizontal supporting members 34 which, at their ends toward the front of the machine, have suitably secured thereto a pair of spaced parallel members 35 each of which is disposed in a vertical plane. Suitably secured to the upper surfaces of the members 35 is a horizontal plate 36 which serves as a table as hereinafter described. Suitably secured to the members 34 toward the rear of the machine is a horizontal plate 37 occupying a lower level than the plate 36. The upper surface of the plate 37 carries a plurality of supporting members 38 extending rearwardly in parallel relation from the table 36, the members 38 being half-round when viewed endwise and the rounded surfaces facing upwardly.

As illustrated in Fig. 2, the hereinbefore described frame extension *f* has suitably secured thereto, as by the bolts 39, one end of a bracket 40 which, at its other end, is welded or otherwise suitably secured to the hereinbefore described angle member 32.

As shown in Figs. 1, 2 and 7, the forwardly facing vertical surface of the angle member 32 has a horizontal plate bracket 41 suitably secured thereto, as by one or more bolts 42. At the same level, the hereinbefore described frame extension *f* has a pair of horizontally extending plate brackets 43 suitably secured thereto as by the bolts 44. The plate brackets 41 and 43, at their forward ends, have a horizontal shaft 45 journaled therein. As shown in Fig. 7, the shaft 45, adjacent that plate bracket 43 toward the right, has secured thereto a ratchet wheel 46 with which is coactable a pawl 47 pivoted on a plate 48 freely oscillatory on said shaft 45, Fig. 9. Connected to the plate 48 by a pin-and-slot connection 49 is one end of a link 50 which extends horizontally from left to right, Fig. 8, freely through an opening provided therefor in the frame extension *f*, the link 50, at its end removed from the plate 48 having one end of a lever 51 pivoted thereto. The lever 51, intermediate its ends, is pivoted at 52 to a U-shaped bracket 53 secured by bolts 54 to said frame extension *f*. The end of the lever 51 removed from the link 50 carries a cam roller 55 coactable with a cam member 56 suitably secured to the rear end surface of the hereinbefore described blanket cylinder 19.

The lever 51 should be biased in a counterclockwise direction, Fig. 8, and, to this end, there may be utilized a member 57 which, at 58, is pivoted to the lever 51. The member 57 extends from right to left, Fig. 8, and the free end there-

of is loosely received within a passage formed in a tubular member 59 suitably secured to the frame extension *f*, as by the bolts 60, said frame extension *f* preferably being provided with a recess disposed in alignment with the passage in the member 59. The member 57 carries a fixed collar 61 engaged by one end of a helical spring 62 encircling said member 57, the other end of the spring 62 engaging the member 59 so as to bias the lever 51 in a counterclockwise direction, Fig. 8.

Referring to Figs. 2, 7 and 8, the shaft 45, adjacent each of the plate brackets 41, 43 and 43, is shown as having sprocket wheels 64 suitably secured thereto for rotatable movement therewith. Each of the plate brackets 41, 43 and 43, at the rear end thereof, carries a sprocket wheel 65, pairs of the sprocket wheels 64, 65 being transversely aligned as indicated in Fig. 2 for the reception of the respective endless sprocket chains 66, 67 and 68 of duplicate character.

As shown in Fig. 10, each transversely extending sleeve 69 of the aforesaid sprocket chains has a screw 70 threaded thereinto, the screw head 70a confining a roller 71 loosely on the screw shank and all of the rollers 71 being disposed in longitudinal alignment.

The plate 37, in the zone of the sprocket chain 66, is provided with a slot 37a, Fig. 2. In operation, the upper span of the chain 66 travels toward the rear of the machine or upwardly as the parts are positioned in Fig. 2, said upper chain span being disposed substantially in the plane of the plate 37 and the rollers 71 extending upwardly through the slot 37a and terminating some distance above the upper surface of said plate 37.

The upper spans of all of the chains 66, 67 and 68 move in the same horizontal plane and the rollers 71 on the chains are aligned, respectively, in groups of three at right angles to the path of chain movement. As shown in Fig. 8, one of the plate brackets 43 has secured thereto a pair of spaced bracket members 72 having horizontally aligned upper surfaces to which a horizontal supporting member 73 is secured by screws 74. As will be obvious, the member 73 serves as a support upon which the upper span of the sprocket chain 67 rests whereby the latter is maintained constantly in a horizontal position. It will be understood that the upper spans of each of the sprocket chains 66 and 68 are supported by an arrangement corresponding with the one described above.

Referring to Figs. 7 and 8, the hereinbefore described frame extension *f*, on the exterior surface thereof, is shown as having a block 76 secured thereto by screws 77. The block 76 is provided with a passage 76a in which is freely received a guide structure 78 comprising a pair of members 79 and 80 secured together by screws 81. The members 79 and 80, in the area thereof toward the left, Fig. 8, are spaced apart to form a horizontal channel or passage 82 and, as shown, the bottom member 79 extends to greater extent toward the left than does the upper member 80. Adjacent the end of the passage 82 toward the right, Fig. 8, the guide structure is provided with a recess in which is freely received a roller 83 mounted on a vertical screw 84. Standing from the upper surface of the guide structure 78 is a lug 85 through which freely extends the shank of a horizontal screw 86 which is prevented from moving with respect to said guide structure 78 by the head of the screw and

a collar 87 secured to said screw, the screw head and the collar engaging opposite respective sides of the lug 85. The threaded end of the screw 86 is received in a horizontal threaded passage provided therefor in the block 76.

As shown in Fig. 7, the frame extension 71, in the area thereof toward the printing cylinders, is provided with a recess having seated therein a block 88 carrying a guide structure 78a which is a duplicate of the guide structure 78 described above. In view of this fact, the same reference characters have been applied to corresponding parts of the two guide structures 78 and 78a.

The guide structures 78 and 78a serve, in the manner hereinafter described, to guide the strip-like articles endwise toward and between the printing cylinders.

Referring further to Figs. 2 and 7, the guide structure 78a is shown as having secured thereto the members 89 which extend horizontally toward the printing cylinders. Secured to the lower surface of each of the members 89 by a screw head 90 is a freely rotatable roller 91, one of the rollers 91 being disposed in alignment with the rollers 88 of the guide structures 78 and 78a, and the other roller 91 being spaced from the roller 88 a distance corresponding with the width of the strip-like article to be fed through the printing zone.

As shown in Fig. 7, the plate brackets 43 have secured to the upper surfaces thereof a plate 89a, the upper surface of which is in horizontal alignment with the top surfaces of the members 88. At the end thereof toward the left, Fig. 7, the plate 89a comprises an upwardly extending section 89b.

Referring to Figs. 6, 7, 8 and 8a, the hereinbefore described gear wheel 13 is shown as secured to a shaft 92 which extends through and is journalled in a unitary structure comprising the disks 93 and 94, said shaft 92 being secured eccentrically to a circular disk 94 journalled in a circular recess formed in one side of the frame extension 71, the shaft 92 extending from right to left, Fig. 8a, through an enlarged passage formed in said frame extension 71 and, at its end, having a roller 95 secured thereto. The disk 93 comprises a laterally extending arm 93a to which is pivoted one end of a link 96 which, at its other end, is of fork-shaped construction as indicated at 96a so as to slide upon and be supported by the projecting end of the hereinbefore described shaft 18, Fig. 6. Immediately adjacent the link 96, the shaft 18 has secured thereto a disk 97 which comprises a cam section 97a coactable with a cam roller 98 secured to said link 96, a suitably anchored spring 96b serving to hold the roller 98 in engagement with the periphery of the disk 97. As indicated in Figs. 7 and 8, the above described roller 95 is coactable with a roller 99 mounted on a horizontal shaft 100 journalled in said frame extension 71, the shaft 100 supporting the hereinbefore described gear wheel 12.

In view of the foregoing, it will become apparent that the shaft 92, under the control of the cam disk 97 and the spring 96b, is adapted to occupy two positions as imposed thereon by movement of the structure comprising the disks 93 and 94, such movement being produced by the link 96. In one of these positions, the roller 95 occupies its feeding position wherein it is spaced from the roller 99 a distance corresponding with the thickness of the article which is to be fed through the printing zone. In the other of these posi-

tions, the roller 95 is "idle" and, at this time, said roller 95 is spaced from the roller 99 a distance somewhat greater than the thickness of the article which is to receive the printing impression. However, the arrangement is such that, in both positions of the roller 95, the gear wheel 13 is in meshing relation with the gear wheel 12.

As indicated in Figs. 1 and 5, a rectangular frame formed by four side members 102 is supported by a bracket 102a carried by the frame F, Fig. 11, and by standards 103 upstanding from a suitable supporting surface. The frame formed by said members 102 carries a plurality of spaced supports 104 the upper surfaces of which are disposed in a horizontal plane and said supports 104 having secured thereto a plurality of spaced supporting members 105, the members 105 being half-round when viewed endwise and the rounded surfaces facing upwardly.

The frame formed by the side members 102, at the respective front and rear sides thereof, has attached thereto members which form bearings for the shafts 106 and 107 which are disposed in parallel relation. As indicated in Fig. 5, the front frame member 102 carries a plurality of brackets 108 forming bearings for the front shaft 106. As hereinafter described, said frame last mentioned has attached thereto a plurality of brackets which form bearings for the shaft 107.

As shown in Fig. 4, the front shaft 106 has secured thereto a plurality of spaced sprocket wheels 110 and, similarly, the rear shaft 107 has secured thereto a plurality of spaced sprocket wheels 111, the sprocket wheels 110 and 111 being aligned in pairs transversely of the machine. Further, as shown in Fig. 4, the pairs of sprocket wheels 110 and 111 carry the respective endless sprocket chains 112, 113 and 114 of duplicate character. As indicated in Fig. 5, the upper spans 35 of the sprocket chains 112, 113 and 114 rest upon suitably supported members 115a to thereby support said upper spans for movement along horizontal paths, respectively.

As shown in Fig. 3, each of the sprocket chains 45 last noted has the usual side links 115 at one side of the chain replaced by side links 116 each of which comprises an upwardly extending arm 117.

Referring to Fig. 4, pairs of the supporting members 105 are disposed relatively close to each other so as to form narrow paths along which travel the upper spans of the respective sprocket chains 112, 113 and 114. These upper spans move horizontally toward the front of the machine and, while thus moving, the arms 117 extend upwardly 55 in vertical relation. As will be understood, the arms 117 are aligned in groups of three at right angles to the path of chain movement.

Referring to Fig. 11, the aforesaid shaft 107 is shown as having a ratchet wheel 118 secured thereto for rotatable movement therewith. Freely oscillatory on the shaft 107 is a plate frame 119 on which is pivoted a pawl 120 coactable with said ratchet wheel 118. Pivoted to the plate frame 119 is one end of an actuating link 121 the other 65 end of which is pivoted to one end of a lever 122 pivoted to a bracket 123 carried by and projecting from the frame F, the lever 122 being biased in a clockwise direction, Fig. 11, by a suitably anchored spring 122a. The other end of the lever 122 carries a cam roller 124 coactable with a cam member 125 secured to and rotatable with the plate cylinder 22.

The frame formed by the members 102 has secured thereto two additional brackets 102a, Fig. 75 4, the outermost of which, at its lower end is bolted

to a plate 126 suitably secured to the frame F, Figs. 4 and 11.

The brackets 102a extend upwardly and form bearings for the hereinbefore described shaft 107. Above this shaft, the upper surfaces of the brackets 102a are horizontally aligned so as to serve as the support for a longitudinally extending angle member 127 having its lower surface provided with three transverse slots 127a, Fig. 13, spaced longitudinally thereof, these slots forming open paths through which travel the respective sets of chain arms 117.

The horizontal section of the angle member 127 has secured thereto a plurality of upwardly extending brackets 128, Fig. 12, in which is journaled a horizontal shaft 129 having secured thereto a plurality of arms 130, Fig. 13. Each of the arms 130 terminates in a downwardly directed section and secured thereto is a gate member 131 corresponding in length and height with the vertical section of the angle member 127.

Secured to the shaft 129 for oscillatory movement therewith is an arm 132, Fig. 13, which terminates in a section 133 formed with an arcuate slot 133a. Secured to the arm section 133 by a bolt 134 extending through the slot 133a is one end of a link 135 which, at its lower end, is connected by a member 136 with one end of a lever 137 and with the upper end of a member 138.

The lever 137 is pivoted at 139 to the lowermost bracket 102a and, on a horizontal axle formed by a bolt extending through the lever 137, there is supported a roller 140 having a peripheral groove 140a which receives the peripheral edge of a disk 141 secured to the shaft 107, said disk 141 having a plurality of spaced notches 141a formed in the outer edge surface thereof.

The member 138, at its lower end, extends loosely through a passage formed in a bracket 142 extending transversely from the frame F. A collar 143 is secured to the upper end of the member 138 and, between this collar 143 and the bracket 142, there is confined a helical spring 144 which encircles the member 138 and biases the lever 137 in a clockwise direction, Fig. 13.

The operation is as follows:

With the electric motor 1 operating at a constant speed, the supporting cylinder 16 is rotated in a counterclockwise direction, Fig. 1, by the mechanical connection comprising the belt 5, the gear wheel 9 and the gear wheel 14. As a result of the rotative movement thus imparted to the supporting cylinder 16, the blanket cylinder 19 is rotated in a clockwise direction, Fig. 1, and, resultantly, the plate cylinder 22 is rotated in a counter-clockwise direction, Fig. 1. As well understood in the art, the blanket cylinder 19 carries an arcuate rubber blanket 19a which, once for each cycle of rotative movement of said blanket cylinder 19, engages and receives an impression from the printing plate, not shown, on the plate cylinder 22, this printing plate, as well understood in the art, receiving ink from the inking rollers 23 as said plate cylinder 22 rotates during operation of the printing press.

Once during each cycle of rotative movement of the blanket cylinder 19, the cam member 56 thereon engages the cam roller 55 to thereby swing the lever 51 in a clockwise direction, Fig. 8, against the force of the spring 62. In response to such movement of the lever 51, the link 50 is moved from right to left, Fig. 8, and, in so doing, causes the pawl 47 to impart a step of rotative movement to the shaft 45. As a result, the upper spans of the three sprocket chains 66, 67

and 68, simultaneously, have a step of movement imparted thereto from the rear of the machine toward the front thereof or from left to right as the sprocket chain 67 is shown in Fig. 8. After the cam member 56 passes beyond the cam roller 55, the lever 51 and the associated parts return, under the influence of the spring 62, to the respective positions thereof shown in Fig. 8. Thereafter, the sprocket chains 66, 67 and 68 remain stationary until the blanket cylinder 19, on its next cycle of rotative movement, again brings the cam member 56 into engagement with the cam roller 55.

As the gear wheel 9 rotates under the control of the electric motor 1 as described above, rotative movement, through the gear wheels 10 and 11, is transmitted to the gear wheel 12, the shaft 12a of which carries the hereinbefore described roller 99. As a result, said roller 99 is rotated continuously in a counter-clockwise direction, Fig. 7. The gear wheel 13, irrespective of the position of the disk 94, Fig. 8a, meshes continuously with the gear wheel 12 and, therefore, responsive to the described rotation of the gear wheels 12 and 13, the roller 95 rotates continuously in a clockwise direction, Fig. 7.

Once during each cycle of rotative movement of the blanket cylinder 19, the cam section 97a of the disk 97, Fig. 6, engages the cam roller 98 to thereby move the arm 93a of the disk 98 in a counter-clockwise direction, Fig. 6. In so doing, the disk 94 is moved rotatably in its seat in the frame extension 51 and, as a result, the roller 95 is moved bodily so as to bring the same 35 into feeding position closely adjacent the roller 99.

Once during each cycle of rotative movement of the plate cylinder 22, the cam member 125 thereon engages the cam roller 124 and moves the lever 122 in a counter-clockwise direction, Fig. 11. As a result, the link 121 is moved from left to right, Fig. 11, whereby the pawl 120 imparts a step of rotative movement to the shaft 107. As a result of this action, the upper spans of the sprocket chains 112, 113 and 114 have a step of rotative movement applied thereto from the rear of the machine toward the front thereof or from right to left as shown in Figs. 4 and 5. After the cam member 125 passes beyond the roller 124, the spring 122a returns the lever 122 and associated parts to the respective positions thereof shown in Fig. 11.

While the sprocket chains 112, 113 and 114 are stationary, the gate member 131 occupies the position shown in Fig. 13. However, when the shaft 107 is actuated as described above, it moves in a clockwise direction, Fig. 13, and carries the disk 141 therewith. As soon as the disk 141 starts to move, a high surface thereof (the surface between an adjacent pair of notches 141a) engages the roller 140 to thereby cause the lever 137 to move in a counter-clockwise direction, Fig. 13. As a result, through the link 135 and arm 132, the shaft 129 is moved rotatively in a counter-clockwise direction, Fig. 13, to thereby elevate the arms 130 and the gate member 131 carried thereby. As the described step of rotative movement of the shaft 107 ceases, the next succeeding notch 141a of the disk 141 comes into registering relation with the roller 140 whereby, under the influence of the spring 144, the parts assume the various respective positions shown in Fig. 13 wherein the gate member 131 is closed with the lower surface thereof resting upon the supporting members 105.

As indicated in Fig. 2, a plurality of the strip-like articles or blanks A may be supported on the table 38. By an operator, these blanks are deposited one-by-one on the supporting members 38 in such manner that each blank takes a position between adjacent rows of the rollers 11, the blanks A, therefore, being disposed at right angles to the path of movement of the sprocket chains 66, 67 and 68.

As the sprocket chains 66, 67 and 68 move step-by-step toward the rear of the machine under the control of the cam member 56, the blanks A move therewith, the angular section 89b of the plate 89a, Fig. 7, being utilized as a register or guide surface into engagement with which the adjacent end surface of each of the blanks A is moved. Eventually, the foremost blank A passes between the guide members 79, 80 of the respective guide structures 78 and comes to rest against the rollers 83. At this time, the foremost blank A is in the path leading through the printing zone and, obviously, by adjustment of the screws 86, the guide structures may be adjusted in a direction at right angles to said path so as to position the blanks A successively therein with the desired degree of precision.

As the foremost blank A thus moves into the path through the printing zone, the roller 95 is in its elevated or "idle" position. The timing is such that, immediately thereafter, the cam surface 97a, in the manner hereinbefore described, causes the roller 95 to move into its feeding position whereby the blank is seized between the constantly rotating rollers 95 and 99 and fed endwise toward and into the printing zone, i. e., the zone between the cylinders 16 and 18 which move the blank therebetween and apply the desired printed impressions thereto. As shown in Fig. 6, the area of the cam surface 97a is small compared with the area of the disk 97 and, therefore, the rollers 95, 99 retain their feeding relation only momentarily or for sufficient time to cause the blank to be fed between the cylinders 16 and 18. During such movement, the rollers 11 adjacent the blank A, the rollers 83 and the rollers 91 cooperate with the respective edges of the blank A to guide the same while reducing friction to a minimum.

As the blank A is thus fed through the printing zone, the sets of sprocket chains 66, 67, 68 and 112, 113, 114 are stationary, and the gate member 131 is in its lower position, Fig. 13. As stated, the sprocket chains 112, 113 and 114 are stationary as the blank A is thus fed through the printing zone and, while thus stationary, adjacent rows of the fingers 117 are disposed on the respective opposite sides of the path of the blank A as it is fed through and from the printing zone, Fig. 13, under the control of the cylinders 16 and 18.

After the printed blank A passes from the printing zone, it assumes a stationary position on the supporting members 105. Immediately after the printed blank A thus assumes its stationary position as stated, the cam member 125 imparts a step of rotative movement to the shaft 107 in a clockwise direction, Fig. 13, whereby the gate member 131 is elevated and the sprocket chains 112, 113 and 114 are moved a step from the rear of the machine toward the front thereof whereby said printed blank A is moved beyond the gate member 131. As soon as this operation is completed, the cam member 125 moves beyond the roller 124 whereupon the sprocket chains 112, 113 and 114 become stationary and the gate member 131 returns to the position shown in Fig. 13.

While the gate member 131 and the sprocket chains 112, 113 and 114 were being actuated as described above, the sprocket chains 66, 67 and 68 were again moved a step toward the rear of the machine to feed the next succeeding blank A into the path leading through the printing zone.

Thus, in the manner described above, the blanks A are deposited on the supporting members 38 so as to be moved step-by-step by the sprocket chains 66, 67 and 68 into the path leading through the printing zone. In succession, the blanks are removed from the zone of said sprocket chains 66, 67, 68 and passed endwise through the printing zone. Thereafter, under the control of the sprocket chains 112, 113 and 114, the printed blanks are moved step-by-step toward the front of the machine, the printed blanks A being removed from said sprocket chains last noted when desired by an operator stationed at that side of the machine.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. The combination with a printing press, of roller means for moving strip-like articles endwise and in succession along a path extending into and through the printing zone, and conveyer chain means for transporting said strip-like articles sidewise and in succession from said path, said roller means and said conveyer chain means being operated in timed relation by cyclic mechanism of said printing press.
2. The combination with a printing press, of roller means for moving strip-like articles endwise and in succession along a path extending into and through the printing zone, conveyer chain means for transporting said strip-like articles sidewise into said path, and conveyer chain means for transporting said strip-like articles sidewise from said path, said roller means and both of said conveyer chain means being operated in timed relation by cyclic mechanism of said printing press.
3. The combination with a printing press, of roller means for feeding articles directly into the printing zone, conveyer means for feeding the articles to said roller means, conveyer means for moving the articles from the path taken thereby while travelling through the printing zone, and means for operating all of said means in timed relation, said last named means imparting intermittent step-by-step movement to both of said conveyer means.
4. The combination with a printing press having plate and blanket cylinders, of roller means for feeding articles directly into the printing zone, conveyer means for feeding the articles to said roller means, conveyer means for moving the articles from the path taken thereby while travelling through the printing zone, and means responsive to rotation of said plate and blanket cylinders for operating all of said means in timed relation.
5. The combination with a printing press, of means comprising the printing press cylinders for moving articles in succession along a path extending through the printing zone, and means

for transporting said articles from said path, said transporting means comprising mechanism for retaining a plurality of said articles thereon in spaced relation with respect to each other, said transporting means conveying the articles along a path angularly related to said first named path.

6. The combination with a printing press, of means comprising the printing press cylinders for moving articles in succession along a path extending through the printing zone, means for transporting said articles into said path, said transporting means comprising mechanism for retaining a plurality of said articles thereon in spaced relation with respect to each other, said transporting means conveying the articles along a path angularly related to said first named path, and means for transporting said articles from said path, said last named transporting means comprising mechanism for retaining a plurality of said articles thereon in spaced relation with respect to each other, said last named transporting means conveying the articles along a path angularly related to said first named path.

7. The combination with a printing press, of means comprising the printing press cylinders for moving articles in succession along a path extending through the printing zone, means for transporting said articles into said path, said transporting means comprising mechanism for retaining a plurality of said articles thereon in spaced relation with respect to each other, said transporting means conveying the articles along a path related at right angles to said first named path, and means for transporting said articles from said path, said last named transporting means comprising mechanism for retaining a plurality of said articles thereon in spaced relation with respect to each other, said last named transporting means conveying the articles along a path related at right angles to said first named path.

8. The combination with a printing press, of means comprising the printing press cylinders for moving articles in succession along a path extending through the printing zone, means for transporting said articles into said path, said transporting means comprising mechanism for retaining a plurality of said articles thereon in spaced relation with respect to each other, said transporting means conveying the articles along a path related at right angles to said first named path, and means for transporting said articles from said path, said last named transporting means comprising mechanism for retaining a plurality of said articles thereon in spaced relation with respect to each other, said last named transporting means conveying the articles along a path related at right angles to said first named path, said first named and said second named transporting means conveying said articles in opposite directions, respectively.

9. The combination with a printing press, of means for feeding articles directly into the printing zone, transporting means for conveying the articles to said feeding means, said transporting means comprising mechanism for retaining a plurality of said articles thereon in spaced relation with respect to each other, transporting means for moving the articles from the path taken thereby while travelling through the printing zone, said last named transporting means comprising mechanism for retaining a plurality of said articles thereon in spaced relation with respect to each other, and means for operating all of said means in timed relation.

10. The combination with a printing press, of means comprising the printing press cylinders for moving articles in succession along a path extending through the printing zone, means for feeding articles directly into the printing zone, transporting means for conveying the articles to said feeding means, said transporting means comprising mechanism for retaining a plurality of said articles thereon in spaced relation with respect to each other, transporting means for moving the articles from the path taken thereby while travelling through the printing zone, said last named transporting means comprising mechanism for retaining a plurality of said articles thereon in spaced relation with respect to each other, and means for operating all of said means in timed relation.

11. The combination with a printing press, of means comprising the printing press cylinders for moving articles in succession along a path extending through the printing zone, means for feeding articles directly into the printing zone, transporting means for conveying the articles to said feeding means, said transporting means comprising a plurality of endless sprocket chains disposed in parallel relation, mechanism associated with said sprocket chains for retaining a plurality of said articles thereon in spaced relation with respect to each other, transporting means for moving the articles from the path taken thereby while travelling through the printing zone, said last named transporting means comprising a plurality of sprocket chains disposed in parallel relation, mechanism associated with said last named sprocket chains for retaining a plurality of said articles thereon in spaced relation with respect to each other, and means for operating all of said means in timed relation.

12. The combination with a printing press, of means for moving strip-like articles sidewise and in succession into a path extending through the printing zone, said moving means comprising mechanism for retaining a plurality of said strip-like articles thereon in spaced relation with respect to each other, means for moving each strip-like article, after it reaches said path, lengthwise between the printing press cylinders, the latter thereafter moving each strip-like article through and from the printing zone, and means for moving said strip-like articles sidewise and in succession from said path, said last named moving means comprising mechanism for retaining a plurality of said strip-like articles thereon in spaced relation with respect to each other.

13. The combination with a printing press, of roller means for moving strip-like articles endwise and in succession along a path extending into and through the printing zone whereby said strip-like articles are engaged successively with the printing press cylinders, the latter thereafter moving each strip-like article through and from the printing zone, conveyor chain means for transporting said strip-like articles sidewise into said path, and conveyor chain means for transporting said strip-like articles sidewise from said path, said roller means and both of said conveyor chain means being operated in timed relation by cyclic mechanism of said printing press.

14. The combination with a printing press, of roller means for moving strip-like articles endwise and in succession along a path extending into and through the printing zone whereby said strip-like articles are engaged successively with the printing press cylinders, the latter thereafter

moving each strip-like article through and from the printing zone, conveyer chain means for transporting said strip-like articles sidewise into said path, and conveyer chain means for transporting said strip-like articles sidewise from said path, said roller means and both of said conveyer chain means being operated in timed relation by cyclic mechanism of said printing press, each of said conveyer chain means comprising a plurality of endless sprocket chains disposed in parallel relation.

15. The combination with the supporting cylinder and blanket cylinder of a printing press, of a pair of rollers spaced from said cylinders and operable to engage opposite respective sides of individual articles to move them in succession along a path extending into and through the printing zone, conveyer means for moving said articles in succession into said path, said conveyer means comprising a plurality of endless sprocket chains disposed in parallel relation, and means for imparting intermittent step-by-step movement to said sprocket chains whereby each article is moved step-by-step toward said path.

16. The combination with a printing press, of conveyer means for moving strip-like articles sidewise and in succession into a path extending through the printing zone of said printing press, said conveyor means comprising a plurality of endless sprocket chains disposed in parallel relation, means for imparting intermittent step-by-step movement to said sprocket chains to thereby move the upper spans thereof step-by-step toward said path, means projecting upwardly from the sprocket chain upper spans for engaging a side of each strip-like article, means for moving said strip-like articles lengthwise and in succession along said path through the printing zone, and means for operating said means for imparting intermittent movement and said last named means in timed relation with said printing press.

17. The combination with a printing press, of conveyer means for moving strip-like articles sidewise and in succession into a path extending through the printing zone, said conveyor means

comprising a plurality of endless sprocket chains disposed in parallel relation, means timed with said printing press for actuating said sprocket chains in unison to move the upper spans thereof step-by-step toward said path, means projecting upwardly from the sprocket chain upper spans for engaging a side of each strip-like article, and means for moving said strip-like articles lengthwise and in succession along said path through the printing zone.

18. The combination with a printing press, of conveyer means for moving strip-like articles sidewise and in succession into a path extending through the printing zone of said printing press, 15 said conveyer means comprising a plurality of endless sprocket chains disposed in parallel relation, means for imparting intermittent step-by-step movement to said sprocket chains to thereby move the upper spans thereof step-by-step toward said path, means projecting upwardly from the sprocket chain upper spans for engaging a side of each strip-like article, spaced supporting members disposed substantially in a horizontal plane and upon which the strip-like articles rest during movement thereof by said sprocket chains, 20 means for moving said strip-like articles lengthwise and in succession along said path through the printing zone, and means for operating said means for imparting intermittent movement and said last named means in timed relation with said printing press.

19. The combination with a printing press, of means comprising the printing press cylinders for moving articles in succession along a path extending through the printing zone, means for transporting said articles from said path, said transporting means comprising mechanism for retaining a plurality of said articles thereon in spaced relation with respect to each other, said 25 transporting means conveying the articles along a path angularly related to said first named path, a gate member disposed between said paths, and means timed with said printing press for opening and closing said gate member.

FREDERICK W. HILL.
